UNITED STATES PATENT OFFICE

171,605

BEVERAGE BOTTLE OR SIMILAR ARTICLE

George Edward Livingston, Louisville, Ky., assignor to The Moxie Company, Needham Heights, Mass., a corporation of Massachusetts

Application September 30, 1953, Serial No. 27,014

Term of patent 14 years

(Cl. D58—8)

To all whom it may concern:

Be it known that I, George Edward Livingston, a citizen of the United States of America, residing in Louisville, in the county of Jefferson and Commonwealth of Kentucky, have invented a new, original, and ornamental Design for Beverage Bottle or Similar Article, of which the following is a specification, reference being had to the accompanying drawing forming a part thereof.

Fig. 1 is a side elevational view of a beverage bottle showing my new design; and

Fig. 2 is a top plan view.

I claim:

The ornamental design for a beverage bottle or similar article, substantially as shown.

GEORGE EDWARD LIVINGSTON.
